W. T. HENSLEY,
ELECTRIC STARTER CLUTCH MECHANISM,
APPLICATION FILED OCT. 5, 1914.

1,285,702.

Patented Nov. 26, 1918.

UNITED STATES PATENT OFFICE.

WILLIAM T. HENSLEY, OF BOUND BROOK, NEW JERSEY, ASSIGNOR, BY MESNE ASSIGNMENTS, TO BOUND BROOK ENGINE & MFG. CO., A CORPORATION OF DELAWARE.

ELECTRIC-STARTER CLUTCH MECHANISM.

1,285,702.

Specification of Letters Patent. Patented Nov. 26, 1918.

Application filed October 5, 1914. Serial No. 864,934.

To all whom it may concern:

Be it known that I, WILLIAM T. HENSLEY, a citizen of the United States of America, and resident of Boundbrook, Somerset county, New Jersey, (residence address 229 Mountain avenue,) have invented a certain new and useful Improvement in Electric-Starter Clutch Mechanism, of which the following is a specification.

10 My invention relates to automatic clutches for connecting an internal combustion engine shaft with the motor generator of an electric starter for automobiles, motor boats or other vehicles. A clutch of the general character to which my invention relates is disclosed in my prior application No. 831,638, filed April 13, 1914; and in the operation of a starter of this character, as fully explained in said co-pending application, the clutch in question must be constructed to first transmit power from the motor-generator (operating as a motor) to the engine shaft, for the purpose of starting the engine, and to then transmit power from the engine to the said dynamo electric machine (operating this time as a generator) for the purpose of charging the storage battery from which electric current is derived for starting the engine. My invention 30 relates more particularly to that portion of the clutch which is necessary for transmitting power from the motor generator to the engine shaft, in starting the engine, but which is thrown out of action and automatically rendered inoperative as soon as the transmission of power is reversed—that is to say, as soon as the engine begins to drive the generator to charge the storage battery. Generally stated, therefore, the object of 40 my invention is to provide a novel and satisfactory clutch mechanism of the foregoing general character, for the purpose stated, having a construction and mode of operation designed more especially with reference to the transmission of power from the motor-generator to the engine, for starting the latter, and whereby certain objections heretofore observed in the use of clutches of this kind and for this particular purpose, such as backlash, jolting and jarring, etc., in starting and stopping the mechanism, are overcome and eliminated or obviated, to a

considerable extent at least, in a simple and effective manner and without interfering with the other functions of the clutch. 55

It is also an object to provide certain details and novel features of construction and combinations tending to increase the general efficiency and desirability of an electric starter clutch mechanism of this particular character. 60

To the foregoing and other useful ends my invention consists in matters herein-after set forth and claimed.

In the accompanying drawings— 65

Figure 1 is a section on line 1—1 in Fig. 2, showing certain portions in elevation, and showing certain portions broken away for convenience of illustration, of an electric starter clutch mechanism embodying the 70 principles of my invention, for use between the engine shaft and the motor generator of the starter.

Fig. 2 is a section on line 2—2 in Fig. 1.

As thus illustrated, my invention comprises the one clutch member A, which is provided with a hub portion *a* adapted to be keyed to the engine shaft, and the other clutch member B which is loose on said shaft. To permit one member to rotate relative to the other, and in order to combine the two members in one unitary clutch structure, the member B, which is in the form of a sprocket wheel or belt pulley, is mounted to turn on the hub *a*, the latter 80 being provided circumferentially thereof with a ball bearing *a*¹ to reduce friction between the two members. The periphery of the member B is provided with sprocket teeth *b*, or with any other suitable means, 85 for connection by a sprocket chain or belt or other means with the shaft of the motor-generator (not shown), it being understood that this motor-generator and its connection to the member B may be of any suitable known or approved character, these being shown in my said prior application. A friction ring *b*¹ is secured to the inner face of the member B, by pins *b*², said ring encircling said ball bearing. A friction ring of 100 larger diameter, such as the ring or band *a*² is secured to the member A, being arranged to encircle the ring *b*¹, it being removably held on the ring *a*³ which is integral with

the member A, and which is disposed between the two friction rings a^2 and b^1 , the rings a^2 and a^3 being keyed together by pins a^6 , or by any other suitable means.

5 The ring a^3 is provided with recesses a^4 at intervals along the inner circumference thereof, which recesses in effect provide cams a^5 , each cam being in the form of a bearing surface which is tangential to a circle having an axis coincident with the axis of the engine shaft. At their ends which are farther away from the axis of rotation, each cam is provided with a pocket a^8 ; and between each cam and the ring b^1 a roller a^7 is interposed in the manner shown. The recesses a^4 are formed in the face of the ring a^3 , and a closure plate a^{10} , secured by screws a^{11} , retains the rollers a^7 in position. The formation of the cam a^5 is such that

10 when the member B is rotated by the motor-generator, in the direction indicated by the arrow, (the clutch never rotates in the reverse direction) the said rollers a^7 are caused to travel along said tangential cams in the direction of the shoulders a^6 , whereby said rollers become tightly wedged between the cams and the ring b^1 , thus causing the member A to rotate positively with the member B in starting the engine. After the engine

15 is started, the transmission of power is then from the member A to the member B, and consequently the rollers a^7 are thrown out of clutching engagement with the ring b^1 , and so far as these rollers are concerned the

20 member A may rotate without communicating any power to the member B, and without driving the motor generator; for at such time the rollers are caught by the pockets a^6 and held out of engagement with

25 the ring b^1 , in a manner that will be readily understood. The brake shoes b^3 , of any suitable character, are pivoted at b^4 , by means of their springy arms b^5 , and by means of a removable screw b^6 inserted

30 through the junction of said arms and into the member B, each brake shoe being adapted to bear upon the ring a^2 for the purpose of driving the member B after the engine has started. The two brake shoes are con-

35 nected together at their other ends by means of a spring b^7 , these springs b^8 and b^9 resisting centrifugal action to yieldingly hold the brake shoes on the friction ring. In other words, and during the rotation of the

40 clutch, the said brake shoes b^3 are thrown outward by centrifugal force, or tend to move outward and this tendency is yieldingly opposed by the said springs, whereby the greater the speed of rotation the less the

45 pressure of the shoes on said ring, and vice versa; and in this way the motor generator is driven at a uniform speed from a variable source of power, for notwithstanding fluctuations in the speed of the automobile

50 or other engine the said generator will ro-

tate at a constant speed because of the variable pressure exerted automatically by the brake shoes on the friction ring a^2 of that member of the clutch which is fixed on the engine shaft.

From the foregoing it will be seen that the rollers a^7 , and also the brake shoes b^3 , are in action when the motor generator is being employed for starting the engine; but after the engine is started, and while the engine is driving the motor-generator to produce current for charging the storage battery, the rollers a^7 are inoperative and are not in action, the brake shoes b^3 being depended upon at this time to transmit power from the one clutch member A to the other clutch member B, thus enabling the motor-generator to operate without any appreciable fluctuations in the speed thereof, notwithstanding that the automobile engine operates at a variable speed. The brake shoes b^3 are preferably provided with carbon blocks or inserts b^8 for engaging the ring a^2 , and said ring is preferably of cast iron or steel or some other metal which will show no appreciable wear, but which to the contrary will take on a high polish as a result of its contact with the carbon of the brake shoes. With the provision of the rollers a^7 , and cams a^5 which coöperate therewith, it is found that various difficulties or objections are overcome or greatly reduced, such as back-lash, jolting and jar-ring, etc., in stopping and starting, that the various functions of the mechanism as a whole are not interfered with in any way whatsoever.

What I claim as my invention is:—

1. A clutch mechanism comprising two rotary members for alternately communicating power to each other, engaging means by which one member communicates power to the other member, and friction means by which power is communicated from said other member to the one member, said members rotating in the same direction for both transmissions of power.

2. A clutch mechanism comprising two rotary members for alternately communicating power to each other, engaging means by which one member communicates power to the other member, and friction means by which power is communicated from said other member to the one member, said members rotating in the same direction for both transmissions of power, and said friction means being disposed radially outside of said engaging means.

3. A clutch mechanism comprising two rotary members for alternately communicating power to each other, engaging means by which one member communicates power to the other member, and friction means by which power is communicated from said other member to the one member, said mem-

bers rotating in the same direction for both transmissions of power, and said means including a friction shoe with a pivotally mounted, flexible end portion, and a spring 5 for yieldingly holding the other end of said shoe in position.

4. A clutch mechanism comprising two rotary members for alternately communicating power to each other, engaging means by 10 which one member communicates power to the other member, and friction means by which power is communicated from said other member to the one member, said members rotating in the same direction for both 15 transmissions of power, said friction means including a friction ring which is removable from the clutch and removable inserts for engaging said ring.

5. A clutch mechanism for connecting an 20 internal combustion engine with the motor-generator of an electric starter, comprising two members arranged to rotate about a common axis, one said member having means for receiving power from the engine, the 25 other member having means for receiving power from the motor-generator, the rotation of said members being always in the same direction, a friction ring for the one member, a friction ring on said other member, cams on the one member, rollers interposed between said cams and the friction ring of said other member, a brake shoe engaging the friction ring of said one member, to transmit power from said other member to the one member, a spring acting in 30 opposition to centrifugal force to reduce the effective pressure of said shoe as the speed of rotation increases, and vice versa, said members being supported for relative 35 movement, said rollers and cams coöperating to rotate the one member when said other member is driven by the motor-generator to start the engine, and said cams permitting the one member to rotate faster than said other member after the engine is started, said 40 rings being disposed between said rings, and the ring of said other member being inside of said rollers.

6. A clutch mechanism for connecting an 50 internal combustion engine with the motor-generator of an electric starter, comprising two members arranged to rotate about a common axis, one said member having means for receiving power from the engine, the 55 other member having means for receiving power from the motor-generator, the rotation of said members being always in the same direction, a friction ring for the one member, a friction ring on said other member, cams on the one member, rollers interposed between said cams and the friction ring of said other member, a brake shoe engaging the friction ring of said one member, to transmit power from said other member to the one member, a spring acting 60 in opposition to centrifugal force to reduce the effective pressure of said shoe as the speed of rotation increases, and vice versa, said 65

in opposition to centrifugal force to reduce the effective pressure of said shoe as the speed of rotation increases, and vice versa, said members being supported for relative movement, said rollers and cams coöperating 70 to rotate the one member when said other member is driven by the motor-generator to start the engine, and said cams permitting the one member to rotate faster than said other member after the engine is started, 75 said cams having pockets at one end thereof to hold the rollers out of action while the engine is rotating the one member faster than said shoe is rotating said other member.

7. A clutch mechanism for connecting an internal combustion engine with the motor-generator of an electric starter, comprising two members arranged to rotate about a common axis, one said member having means 80 for receiving power from the engine, the other member having means for receiving power from the motor-generator, the rotation of said members being always in the same direction, a friction ring for the one member, a friction ring on said other member, cams on the one member, rollers interposed between said cams and the friction ring of said other member, a brake shoe engaging the friction ring of said one member, 85 to transmit power from said other member to the one member, a spring acting in opposition to centrifugal force to reduce the effective pressure of said shoe as the speed of rotation increases, and vice versa, said members being supported for relative movement, 90 said rollers and cams coöperating to rotate the one member when said other member is driven by the motor-generator to start the engine, and said cams permitting the one member to rotate faster than said other member after the engine is started, said 95 rings having smooth peripheries for engaging said roller and shoe, and said cams being disposed between said shoe and rollers. 100

8. A clutch mechanism for connecting an internal combustion engine with the motor-generator of an electric starter, comprising two members arranged to rotate about a common axis, one said member having 115 means for receiving power from the engine, the other member having means for receiving power from the motor-generator, the rotation of said members being always in the same direction, a friction ring for the one member, a friction ring on said other member, cams on the one member, rollers interposed between said cams and the friction ring of said other member, a brake shoe engaging the friction ring of said one member, to transmit power from said other member to the one member, a spring acting in 120 opposition to centrifugal force to reduce the effective pressure of said shoe as the speed of rotation increases, and vice versa, said 125 rings having smooth peripheries for engaging said roller and shoe, and said cams being disposed between said shoe and rollers. 130

members being supported for relative movement, said rollers and cams coöperating to rotate the one member when said other member is driven by the motor-generator to start the engine, and said cams permitting the one member to rotate faster than said other member after the engine is started, the friction ring for said shoe tightly encircling

said cams, and a removable plate for holding said rollers against displacement.

Signed by me at Boundbrook, New Jersey,
this 22d day of September, 1914.
